UNITED STATES PATENT OFFICE.

CHARLEY ADAMS, OF LEATHA, KENTUCKY.

CLAMP.

Application filed April 16, 1926. Serial No. 102,521.

This invention relates to clamps for associating a pump jack rod and equalizer and which contemplates the provision of companion plates receiving the pump jack rod and equalizer yoke therebetween and one of which provides obliquely disposed locking fingers received within correspondingly disposed cut out portions provided in its companion plate. 5
With the above and other objects in view the invention further includes the following novel features and details of construction to be hereinafter more fully described, illustrated in the accompanying drawing and 10 pointed out in the appended claims. 15

In the drawing:

Figure 1 is an elevation of the invention as applied when in use.

Figure 2 is a side elevation thereof.

20 Figure 3 is a transverse section taken on line 3-3 of Figure 2.

Figure 4 is a longitudinal section taken on line 4-4 of Figure 1.

25 Figures 5 and 6 are plan views of the inner sides of the respective companion plates.

Referring to the drawing in detail wherein like characters of reference denote corresponding parts. The reference character 10 indicates a yoke linked with a companion 30 like 11 arranged upon an equalizer, not shown, while a pump jack rod 13 has its end normally interposed between the corresponding inner sides of the yoke 10; the respective ends of the yoke and rod 13 having heads 12 formed integrally thereon. 35

The invention resides in the provision of companion locking plates 14 and 15 respectively; each of which providing semi-circular central portions 16 upon their corresponding inner sides and defining partitions 17 therebetween, in the manner as clearly illustrated in Figures 5 and 6 of the drawing. The partitions defined upon the inner side of the locking plate 14 having spaced 40 parallel obliquely disposed locking fingers extending therefrom and adapted for reception within correspondingly disposed cut out portions 19 provided in the corresponding portions on the inner side of the locking plate 15, substantially as illustrated in Figure 4 of the drawing. 45

From the illustration in Figures 1 and 2 of the drawing is to be noted that the locking fingers 18 when extending within the cut out 50 portions 19 of its companion locking plate 15 will be held relatively associated when the

rounded heads 12 provided upon the end portions of the yoke 10 and pump jack rod 13 abut the opposite ends of the companion plate 15 and 16 respectively. 60

It is manifest and apparent that the meeting ends of the yoke 10 and pump jack rod 13 may be readily and easily associated upon the application of the above entitled invention when used in conjunction therewith. 65

The invention is susceptible of various changes in its forms, proportions and minor details of construction and the right is herein reserved to make such changes as properly fall within the scope of the appended 70 claims.

Having thus described my invention what is claimed is:—

1. A yoke and rod clamp comprising companion plates, said plates providing registering grooves for association with the yoke and rod, one of said plates having cutout portions extending therethrough, and locking fingers carried by another of the plates and received within the cutout portions for 80 retaining the yoke and rod against displacement. 75

2. A clamp comprising companion plates having a plurality of spaced parallel semi-circular grooved portions provided upon their corresponding inner sides for receiving the respective ends of a yoke and a rod operating a pump jack, said plates defining partitions between the grooves thereof, locking fingers arranged in obliquely disposed portions upon the partitions of one of the plates, and the remaining plate having correspondingly disposed cutout portions for receiving the fingers therein. 85

3. A clamp comprising companion plates having a plurality of spaced parallel semi-circular grooved portions provided upon their corresponding inner sides for receiving the respective ends of a yoke and a rod operating a pump jack, said plates defining partitions between the grooves thereof, one of said plates having upwardly and obliquely disposed locking fingers, the remaining plate having correspondingly disposed cutout portions to receive said fingers, and the ends of 95 the yoke and pump jack rod having enlarged heads abutting the adjacent ends of the plates for retaining the locking fingers against displacement within the cutout portions. 100

105 In testimony whereof I affix my signature.
CHARLEY ADAMS.
